SYSTEM OF CIRCUIT CONTROL

Joseph J. Rosecky, Milwaukee, Wis., assignor to
Cutler-Hammer, Inc., Milwaukee, Wis., a corporation of Delaware

Application May 20, 1940, Serial No. 336,173

6 Claims. (Cl. 171—119)

This invention relates to improvement in systems of circuit control, and more particularly to illumination control systems comprising a plurality of lamp circuits which provide for presetting a plurality of intensities of illumination for each circuit and effecting transition from each preset intensity to another at selective rates for the several circuits, which rates are proportional to the degrees of change in illumination intensities to be effected in the respective circuits.

An object of the invention is to provide a simple system of the aforementioned character which is equally applicable to a variety of voltage control apparatus for the lamp circuits.

Another object is to provide a system which may employ resistance or reaction type of potentiometers for piloting or controlling the sender control circuits.

Another object is to provide a system including individual circuit and master controls whereby transition of the intensity of illumination of an individual circuit from one preset value to another upon transfer from one master circuit to another may be effected in a gradual and continuous manner.

Another object is to provide a remote control system of the aforementioned nature in which a control current between the individual circuit control and the receiver flows only during changes in the illumination intensity of the respective lamp circuit.

Another object is to provide an illumination control system including a plurality of preset master controllers combined with a single selector, and with individual intensity control means for the respective lamp circuits.

Other objects and advantages will hereinafter appear.

An illumination control system of the aforementioned type is illustrated and described in a copending application of Richard B. Hunter, Serial No. 280,448, filed June 22, 1939, and assigned to the same assignee as the present invention (which application has resulted in Patent No. 2,225,994, granted December 24, 1940), the present invention differing from the disclosure of said Hunter application in respect of providing a single fader control unit cooperating with a plurality of scene and/or group master controllers to provide for presetting a plurality of scenes and to gradually change from one scene preset to another.

The accompanying drawing is a diagram of a system incorporating the invention. The system

comprises two groups of lamps 1 and 2, respectively. Energy is supplied to the lamps and to the control circuits from the alternating current bus bars L¹ and L². The current for the lamps 1 is supplied through an auto-transformer dimmer 3 which has its primary winding connected across the lines L¹, L² and which is provided with a sliding contact brush 4 by means of which a variable secondary voltage derived from the transformer may be impressed upon the lamps. The brush 4 connects the various taps of the transformer winding selectively with a bar 5 to which one terminal of the lamp circuit is connected, while the other terminal of the lamp circuit is connected to the line L². The brush 4 may be moved along the transformer taps and bar 5 by a screw 6 which is driven by a motor 7, provided with reversing windings, and which motor is controlled by a relay 8.

The relay 8 comprises a lever 3^a, pivoted at its center and provided at each of its ends with magnet cores 8^b, said lever being normally biased to an intermediate or neutral position by any suitable means, such as a spring (not shown). The cores 8^b are surrounded by polarizing coils 8^c which are so wound and so connected across the lines L¹, L² that the polarity of both cores is in the same direction. A second set of coils 8^d is arranged on the cores 8^b, but wound in opposite directions relatively to each other so that a current flowing therein unbalances the pull on the two cores to cause rotation of the armature in one direction or the other, depending upon the direction of the current in the coils 8^d. The lever 3^a is provided with a contact arm 8^e which when the lever rotates makes contact with stationary contacts 8^f or 8^g, to thereby energize one or the other of the reversing windings of the motor 7 and cause the latter to rotate in a corresponding direction.

The circuit arrangement for the lamps 2 and any other additional like circuits is the same as that thus far described for the lamps 1.

The system illustrated further includes a fader control potentiometer 11 which may be of the resistance or the auto-transformer type, the latter type being illustrated. The potentiometer 11 is connected with its end terminals across the lines L¹, L² and is provided with a sliding contact 11^c by means of which the value of the derived voltage may be varied. A master potentiometer 12 comprising two like sections 12^a and 12^b which sections are connected between the contact 11^c on one hand and the lines L² and L¹, respectively,

on the other hand. The sections 12^a and 12^b are provided with sliding contacts 12^c and 12^d, respectively, by means of which a variable output voltage may be obtained. Each lamp circuit is 5 provided with a center tap potentiometer 13, comprising the sections 13^a and 13^b and having its center tap connected to the contact 11^c, while the end terminals are connected to the contacts 12^c and 12^d, respectively. Each lamp circuit also 10 includes similar transformers 14 and 15, the secondary windings 14^b and 15^b, respectively, of which are connected in series with each other between the brush 12^d and the coils 8^d, a circuit being completed over a contact bar 16, to the 15 adjustable brush 17^b, of a variable rheostat 17^a which is connected across the lines L¹, L². The brush 17^b is insulatedly connected to the brush 4 to move therewith, so that the potential of the brush 17^b with respect to the lines L¹ and L² is 20 a function of the voltage impressed upon the lamps 1. The primary winding 14^a of transformer 14 is connected between the brush 11^c and the adjustable contact 13^d of the lower half 13^b of potentiometer 13, while the primary winding 25 15^a of transformer 15 is connected between the adjustable contact 11^c and the adjustable contact 13^c of the upper half of said potentiometer.

The system is shown in the drawing in a transition from one scene setup to another. It may 30 be assumed for purposes of description that the brush 11^c was previously at the bus bar L¹ and that it is now being moved toward the bus bar L². The voltages impressed upon the scene master potentiometers 12^a and 12^b are at all 35 times equal to the voltages of the respective sections 11^a and 11^b—said voltages, as aforeindicated, varying from maximum to minimum, according to the position of brush 11^c. Furthermore, at any moment the output voltages of the 40 sections 12^a and 12^b are a fraction of the aforementioned input voltages dependent upon the setting of the brushes 12^c and 12^d. These output voltages are impressed upon the potentiometer sections 13^a and 13^b, whose modified output voltages are in turn impressed upon the primary windings 14^a and 15^a of transformers 14 and 15, 45 respectively. Thus when the brush 11^c is at the bus bar L¹, the value of the voltage impressed upon the transformer 14 is zero, while the value of the voltage adapted to be impressed upon the transformer 15 is a maximum (namely, the voltage across L¹, L²), whose value is modified by 50 the setting of the contacts 12^c and 13^c which thus control the brilliancy of the lamps 1. That is to say, a voltage is induced in the secondary winding 15^b of transformer 15 which causes a flow of current through the coils 8^d to operate motor 7 in the proper direction until the voltage between brush 17^b and line L¹ equals in polarity 55 and magnitude the induced secondary voltage, at which point the motor 7 stops and the lamps operate at the desired intensity. The aforedescribed arrangement or circuit connection of secondary windings 14^b and 15^b is such that the voltages induced therein when the contact 11^c is in an intermediate position are opposed to 60 each other, thus providing a differential voltage value. Moreover, the relative values of the opposed voltages last mentioned will be additionally dependent upon the respective positions of contacts 12^c and 13^c and contacts 12^d and 13^d.

If it should be desired to change the illumination intensity of a single group of lamps it is 65 only necessary to change the adjustment of the brush 13^c or 13^d associated with the respective

group of lamps, whereas the illumination intensities of all of the groups of lamps may be modified jointly and proportionally by adjustment of the brush 12^c or 12^d, depending upon the extreme position or polarity of the contact 11^c.

If it is desired to preset for a third or other succeeding scene while contact 11^c is at the bus bar L¹, it is only necessary to adjust the contacts 12^d and 13^d to the desired value, and when it is desired to change to the new set-up, contact 10 11^c is moved from L¹ to L² with the result that the intensities of all lamp groups are changed from the respective previous values to the new values gradually and proportionally relatively to each other. In any intermediate position of the 15 contact 11^c the effect of the adjustments of the scene masters and group scene potentiometers will be proportional to the settings of the various adjustable contacts as will be obvious.

When the desired values of the respective 20 lamp circuit voltages have been attained for a given scene no current flows in the circuits of the relay coils 8^d associated with the respective lamp circuits between the several receiving and sending stations and the various control circuits 25 which provided the particular intensities might therefore be opened if desired.

What I claim as new and desire to secure by Letters Patent is:

1. A control system comprising, a circuit to be 30 controlled, means for presetting a plurality of operating values for an electrical condition of said circuit, comprising, a pair of fixed ratio transformers having primary and secondary windings, said secondary windings being connected in series relation to each other and having output voltages opposed to each other, an individual voltage regulator for each of said primary windings, affording a variable ratio between its input voltage and its output voltage, 40 the input circuits of said voltage regulators being connecting in series across a voltage source and a potentiometer having an adjustable contact for varying the potential thereof relative to the potential of its end terminals and connected to 45 the common point of said individual voltage regulators, whereby the voltage of one of said latter regulators is increased and the voltage of the other is simultaneously decreased.

2. An illumination control system comprising 50 a circuit to be controlled, means for presetting a plurality of operating values for an electrical condition of said circuit, comprising, a pair of voltage regulators, means individual to each of said regulators for varying the output voltage 55 thereof and impressing it upon said circuit, a second pair of voltage regulators, one for each of said first pair of voltage regulators and also affording a variable ratio of their input and output voltages and adapted to cooperate with the 60 respective voltage regulator of the first pair to impress their respective output voltages thereon, and means to increase the input voltage of one and to simultaneously decrease the input voltage of the other of said second pair of voltage regulators. 65

3. A control system comprising, a circuit to be controlled, means for presetting a plurality of operating values for an electrical condition of said circuit, comprising, a pair of transformers 70 having primary and secondary windings, said secondary windings being connected in series relation to each other and having output voltages opposed to each other, a voltage regulator for each of said primary windings affording a 75

variable ratio between its input voltage and its output voltage, and adapted to impress the latter upon the respective primary winding, and means for increasing the input voltage of one and simultaneously decreasing the input voltage of the other of said voltage regulators.

4. A control system comprising a circuit to be controlled, means for presetting a plurality of operating values for an electrical condition of said circuit, comprising, a pair of transformers having primary and secondary windings, said secondary windings being connected in series relation to each other and having output voltages opposed to each other, a potentiometer for each of said primary windings, means to vary the output voltage of each of said potentiometers and to impress it upon the respective primary winding, and means for increasing the input voltage of one and simultaneously decreasing the input voltage of the other of said potentiometers.

5. A control system comprising a circuit to be controlled, means for presetting a plurality of operating values for an electrical condition of said circuit, comprising, a pair of transformers having primary and secondary windings, said secondary windings being connected in series relation to each other and having output voltages opposed to each other, a potentiometer for each of said primary windings affording a variable ratio of its input voltage and its output voltage and impressing it upon the responsive primary winding, a second pair of variable potentiometers, one for each of said first pair of potentiome-

ters, each of said second pair of potentiometers being adapted to impress its output voltage upon its respectively associated potentiometer of said first pair, and means for increasing the input voltage of at least one of the respectively associated potentiometers of said first and second pairs and simultaneously decreasing the input voltage of at least one of the other respectively associated potentiometers of said first and second pairs.

6. A control system comprising a circuit to be controlled, means for presetting a plurality of operating values for an electrical condition of said circuit, comprising, a pair of transformers having primary and secondary windings, said secondary windings being connected in series relation to each other and having output voltages opposed to each other, a potentiometer for each of said primary windings affording a variable ratio of its input voltage and its output voltage and impressing it upon the respective primary winding, a second pair of variable potentiometers, one for each of said first pair of potentiometers, each of said second pair of potentiometers being adapted to impress its output voltage upon its respectively associated potentiometer of said first pair and means for increasing the input voltage of one of said second pair of potentiometers and simultaneously decreasing the input voltage of the other of said second pair of potentiometers.
